UNITED STATES PATENT OFFICE.

CHARLES WHITTAKER, OF CHICAGO, ILLINOIS.

FAUCET.

SPECIFICATION forming part of Letters Patent No. 248,971, dated November 1, 1881.

Application filed June 8, 1881. (No model.)

To all whom it may concern:

Be it known that I, CHARLES WHITTAKER, a citizen of the United States, residing at the city of Chicago, in the county of Cook and State of Illinois, have invented certain new and useful Improvements in Faucets; and I do hereby declare the following to be a full, clear, and exact description of the invention, such as will enable others skilled in the art to which it applies to make and use the same, reference being had to the accompanying drawings, and to the letters or figures marked thereon, which form a part of this specification.

My invention relates to improvements in that class of faucets which are adapted to be connected with both hot and cold water pipes, and by which the hot and cold water may be mingled together in equal portions or in any proportions desired before escaping, and by which either the hot or cold water may be drawn separately. An index-plate is provided, which shows the proper place to adjust the handle, whereby the temperature of the stream may be known without testing the same.

My invention is further explained by reference to the accompanying drawings, in which—

Figure 1 represents a vertical section drawn on line *x x* of Fig. 3. Fig. 2 is a side view of the cam. Fig. 3 is a horizontal section. Fig. 4 is a top view. Fig. 5 is a side view.

A is the valve-chamber.

B is the hot-water inlet, which is provided with stopper C.

D is the cold-water inlet, which is provided with stopper E. The stoppers C and E are respectively provided with valve-rods F and G. Ways H H are formed upon the respective sides of the chamber for the reception of the slides I I. The slides I I are moved upward and downward by cam J, whereby the respective hot and cold water passages are opened and closed. The cam J is rigidly secured to the stem M, and is moved with it as the handle N is moved.

O is the index-plate, upon which the words "Hot," "Cold," "Medium," and "Stop" are written, thus indicating the proper places of adjusting the handle to produce the results thus indicated.

The stoppers are formed of rubber or other elastic substances in the ordinary manner.

The case or chamber A may be cast in a single piece, and the cover or index plate O secured thereto by a screw-joint, as shown.

That portion of the cam J between 1 and 2 forms a true horizontal plane which extends at right angles to the vertical stem M. The part between 2 and 3 and 1 and 3, respectively, inclines downward, forming an obtuse angle from the highest to the lowest point in the cam.

As thus far described, my invention is substantially like my previous invention, for which application for Letters Patent of the United States was filed April 12, 1881.

My improvements upon said previous invention consist in substituting the simple cam J for the two cams previously used; also, in the peculiar construction of said cam and of the peculiar relative arrangement of the slides and stoppers to said cam, whereby a single cam will perform all and the same functions which in my said previous device required two cams. This end is accomplished by forming about one-third of the area of said cam J, consisting of that part between 1 and 3 and 2 and 3, upon different inclined planes, as shown by the dotted lines in Fig. 2, and by locating the hot and cold water valves both upon one side of the center, as seen in Figs. 3 and 4, whereby both valve-slides may simultaneously rest upon the horizontal portion of said cam, and both stoppers be thereby retained in a closed position at the same time.

My invention consists, further, in providing the respective slides I I with anti-friction rollers b b b b, between which the cam J moves as the handle is turned. Also, in providing the spout P and the tube R, respectively, with stop-cocks S and T, by which stop-cocks the course of the water may be readily changed. When the stop-cock S is closed the water will flow through tube R. When stop-cock T is closed and stop-cock S is opened the water will take the ordinary course through the spout. The words "Hot" and "Cold" are located one side of the center, conforming to the change of position of the hot and cold water valves.

My faucet is operated as follows: When the handle N is moved to the word "Hot" the slide I is moved downward by the cam J, whereby the hot-water valve C is opened, while the slide I is simultaneously acted upon by the oppo-

site side of the cam and moved in the opposite direction, whereby the cold-water valve E is closed. When the handle is moved from the word "Hot" to "Stop," the upward incline of cam J, acting upon the slide I, draws the stopper C upward and closes the hot-water valve, while the horizontal portion of said cam moves through the slide I without changing its level, while it retains the stopper unmoved in its closed position. Thus both passages are closed and the flow of water stopped. When the handle is moved on from the word "Stop" to the word "Cold" the horizontal portion of cam J, between 1 and 2, moves through the recess in slide I without changing its position, and it retains the stopper C unmoved in its closed position, while the angular portion of said cam acts upon slide I, forcing it downward, whereby the cold-water valve or stopper E is opened.

- o When the handle is moved on from "Cold" to "Medium," the respective slides are acted upon by the incline portion of the cam, and are both thereby simultaneously thrown halfway open, whereby the hot and cold water is mingled together in equal proportions.

It is obvious that by moving the handle from the word "Medium" toward the word "Hot" the hot-water valve will be thrown more widely open, while the cold-water valve will be partially closed, whereby an excess of hot water is caused to flow. Also, that when the handle is inversely moved from the word "Medium" toward the word "Cold" the opposite result is produced. Thus it is obvious that the flow of water from the faucet may be readily graduated from cold to hot or from hot to cold to any temperature desired.

Having thus described my invention, what I claim as new, and desire to secure by Letters Patent, is—

40

1. In a hot and cold water graduating faucet, the cam J, forming three distinct planes, one horizontal and two inclined, conversely arranged, as connected with the handle and the hot and cold water valves or stoppers, said cam being adapted to move said stoppers both simultaneously and alternately in opposite directions or retain them both at the same time in a closed position, as set forth.

45

2. In a hot and cold water graduating faucet, the combination of the case A, upwardly-extending tube R, spout P, stop-cocks S and T, said stop-cocks being adapted to change the course of the stream from a downward to an upward direction or inversely in the opposite direction, as desired, substantially as and for the purpose set forth.

50

3. In faucets, the combination of the slides II, anti-friction rollers b b b b, and cam J, substantially as set forth.

60

4. In a hot and cold water graduating faucet, the combination of index-plate O, having the words "Hot" and "Cold" printed thereon, both at one side of the center above the respective hot and cold water valves, stem M, handle N, cam J, slides I I, valve-rods F and G, stoppers B and E, all substantially as and for the purpose set forth.

In testimony whereof I affix my signature in presence of two witnesses.

CHARLES WHITTAKER.
